OUTDOOR LIGHTING FIXTURE HOUSING

Fred M. Gore, Carrollton, Tex., assignor to
Lans-Cube, Inc., Dallas, Tex.

Filed May 1, 1970, Ser. No. 22,754

Term of patent 14 years

Int. Cl. D26—03

U.S. Cl. D48—31

FIG. 1

FIG. 2

FIG. 3

FIG. 4

FIG. 5

FIG. 1 is a perspective view of an outdoor lighting fixture housing of my new design;

FIG. 2 is a rear elevational view thereof;

FIG. 3 is a front elevational view thereof;

FIG. 4 is a top plan view thereof;

FIG. 5 is an elevational view of the side opposite that shown in FIG. 1.

I claim:

The ornamental design for an outdoor lighting fixture housing, substantially as shown and described.
